LOOPER AND FEEDING MECHANISM FOR
SEWING MACHINES

Clarence C. Smith, Chicago, and George Sauer, Berwyn, Ill., assignors to Union Special Machine Company, Chicago, Ill., a corporation of Illinois

Application February 5, 1938, Serial No. 188,837

10 Claims. (Cl. 112—215)

This invention relates to looping and feeding mechanism for sewing machines; and it has reference more particularly to looping and feeding mechanism for sewing machines of the type 5 wherein the looping and feeding mechanism is disposed below the work supporting surface and arranged to be operated from a horizontal shaft at the level above the work support.

The chief aim of our invention is to secure a 10 more perfect balance between the looping and the feeding elements, and at the same time to reduce in number the parts required for their actuation, with a view toward minimizing vibration and thereby enabling operation of the 15 sewing machines at higher speeds than possible heretofore, and attaining a correspondingly increased output or production from them.

This desideratum we realize in practice, as hereinafter more fully disclosed by arranging 20 the looper shaft and the feed bar in parallelism and providing a double arm rocker which is medially-fulcrumed to oscillate about a transverse axis intermediate the looper shaft and the feed bar with its opposite extremities connected 25 to the shaft and the bar in such manner that the latter are longitudinally reciprocated contrariwise to induce needle-approaching and needle-avoiding movements of the loopers and feeding movements of the feed dog.

30 In connection with the looping and feeding mechanism wherein the looper shaft and the feed bar are longitudinally reciprocated contrariwise as above set forth, it is a further aim of our invention to enable impartation of oscillatory 35 movements to the looper shaft and thereby induce loop taking and retractive movements of the looper, and rocking movements to the bar and in turn induce up and down or lift movements of the feed dog without interfering with 40 the reciprocation of these elements. This objective we also attain as hereinafter more fully disclosed, through provision of an actuating crank on the looper shaft, a transversely pivoted support in which the needle bar is guided in 45 its longitudinal reciprocation, and connection whereby the pivoted needle bar support and the looper shaft crank are actuated from the same means which operates the rocker.

Another object of our invention is to afford 50 the feed bar support against lateral vibration and bending through provision therefor of a pivoted sleeve in which it is effectively held incident to moving endwise.

55 Another object of our invention is to secure the foregoing advantages in looping and feeding mechanism whereof the component parts lend themselves to ready manufacture and assembling at small cost.

60 Other objects and attendant advantages will

appear from the following detailed description of the attached drawings, wherein

Fig. I is a view partly in side elevation and partly in longitudinal section of a sewing machine embodying our improved looping and feeding mechanism.

Fig. II is a plan view of the work support of the machine with its cover members removed.

Fig. III is a longitudinal sectional view of the work support.

Fig. IV is a fragmentary view showing the front end of a work support in plan.

Fig. V is a horizontal detail section of the rear end of the work support taken as indicated by the arrows V—V in Fig. III.

Figs. VI, VII, VIII, IX and X are detail cross sectional views taken as indicated respectively by the arrows VI—VI, VII—VII, VIII—VIII, IX—IX, and X—X in Fig. III.

The sewing machine chosen for convenience 20 of exemplifying our invention is of the feed-off-the-arm type, generally like the one illustrated and described in U. S. Patent #1,741,095, granted on Dec. 24, 1929, to Norman V. Christensen and Harold J. LeVesconte, in that it has a frame 25

with a horizontal tubular elevated portion 1 which is integrally formed with a bracket-like base 2, and a pendant hollow vertical portion 4 whereto is detachably connected a hollow horizontal work-supporting arm 3, the free end of which underreaches a laterally projecting head 5 at the corresponding end of said elevated tubular portion. Guided for vertical reciprocation in the head 5 is a bar 6 whereto a pair of needles 7 are secured at the lower end. Also confined 30 to axial movement in the head 5 is a vertical presser bar 8 which carries a presser foot 9 at its lower end. Through suitable connections (not illustrated), up and down movements are induced in the needle bar 6 from a shaft 10 which extends longitudinally through the tubular frame portion 1. As shown, the shaft 10 protrudes through a bearing 11 at the front end of the machine where it is provided with a combined hand and belt wheel 12 so that the machine 40 may be operated either manually or by power. At its inner end the shaft has journal support in a bearing 13 set into a partition 15 which extends crosswise of the hollow tubular frame portion 1 and which constitutes a continuation of 45 the side wall 16 of the vertical frame portion 4. Within the hollow of the vertical frame portion 4 at a level intermediate the work support 3 and the needle actuating shaft 10 is a parallel countershaft 17 which is driven, through a pair of intermeshing spur gears 18, 19, from said needle shaft, and which is journaled at opposite ends in bearings 20, 21, respectively set into the opposite side walls 16 and 22 of said vertical frame portion. The countershaft 17 is formed with a 50

55

55

60

60

plurality of rotary actuators in the form of cranks 23, 24 and 25 which through drop links 26, 27, 28 serve to actuate our improved complementary stitch-forming and feeding mechanism 5 in a manner presently explained. The countershaft and gear construction just described constitutes the subject matter of a separate patent application Serial No. 188,836 filed by us concurrently herewith.

10 The complementary stitch-forming and feeding means with which the present invention is more especially concerned is housed within the hollow of the work supporting arm 3, and as shown in Figs. II-X, includes a longitudinally extending 15 shaft 30 which is journaled in spaced bearings 31, 32 and 33 at the bottom of the work support with capacity for both endwise and oscillatory movement. Secured to the outer end of the shaft 30 is a holder 34 for a pair of loopers 35 20 arranged to cooperate in a well known manner with the needles 7 in stitch formation. The shaft 30 is reciprocated endwise to induce needle-avoiding movements in the loopers 35 through a link 37. At one end, the link 37 is pivoted to 25 a laterally-projecting stud 38 of a cross head 39 confined between a pair of fixed collars 40 on the looper shaft 30, and at its other end, said link carries a stud 41 capable of adjustment along a longitudinal slot in the pendant extremity 42a 30 of a double arm rocker 42 affixed to a transverse shaft 43 at a level intermediate said looper shaft and an overlying feed bar 46. As shown in Figs. V and X, the transverse shaft 43 has its opposite ends journaled in bearings 47, 48 whereof the former is set into one of the side walls of the work arm 3, and the latter into an upstanding lug 49 within said work arm. From Figs. III and IX, it will be observed that the cross head 39 has a downward-projection 50 which engages 35 within the interval between longitudinally-arranged guide blocks 51 at the bottom of the work arm 3. To the inner end of the looper shaft 30 beyond the bearing 33 is secured a crank arm 52 with a laterally-projecting stud 53 which is connected to the lower end of the link 28 suspended from the actuator crank 25 on the countershaft 17.

In accordance with our invention, the feed bar 46 is of circular cross section and tubular, and 40 into its outer end is force-fitted the cylindric projecting end 54a of the square shank 54 of a supporting head 55 whereto is secured, with capacity for up and down adjustment in a manner similar to that disclosed in another copending 45 patent application Serial Number 14,595, filed by Hans Hacklander and George Sauer (one of the present applicants) on June 22, 1937, a feed dog 56. In the present construction, the feed bar 46 is supported for endwise sliding movement in a 50 pivoted slideway having the form of a supporting sleeve 57 which is medially pivoted to rock about a transversely extending pin 58 whereof the ends are engaged in inwardly-projecting bosses 59 and 60 at opposite sides of the work 55 support 3. The bar 46 is reciprocated within the sleeve 57 to induce feeding movements of the feed dog 56, through a link 61 which, at one end is pivotally connected to a head 62 at the rear end of said bar, said head having its shank 62a 60 extending into said bar and secured by a clamp collar 63. At its other end, the link 61 carries a clamp screw stud 64 arranged for adjustment along the longitudinal slot in the upward extremity 42b of the double arm rocker 42. Integrally formed with the rocker 42 is a rear-

wardly-extending horizontal arm 42c, which carries a ball stud 65 whereby it is connected to the lower end of the vertical link 27 which extends down from the crank 24 on the countershaft 17. Up or down or lift movements are communicated to the feed dog 56 as a result of rocking of the sleeve 57 about the pivot 58, such motion being imparted from the crank 23 on the countershaft 17 through the link 26, which, at its lower end is coupled with a ball stud 66 on an arm 57a extending rearwardly from said sleeve. Rotation of the feed bar 46 is prevented as a consequence of engagement of the squared shank 54 of the feed dog-supporting head 55 in a correspondingly-configured recess 68 in the outer end wall 15 67 of the work arm 3, see Figs. II and VII. The teeth of the feed dog 56 operate through the longitudinal slots of a throat plate 69 secured cantilever-fashion to the outer end of the work arm 3 by screws 70. The parts within the work 20 arm 3 are accessible from above upon removal of a top cover plate shown at 71 in Figs. III, VIII and IX, and the loopers 35 and the feed dog 56 are exposed for the purposes of inspection or adjustment upon withdrawal of a removable end 25 cap indicated at 72 in Figs. I, III, IV, VI and VII.

The operation of the mechanism is as follows:

By the action of the crank 24 on the countershaft 17 upon the link 27, the medially-fulcrumed double arm rocker 42 is continually oscillated, and through it and the associated horizontal links 37 and 61, the looper shaft 30 and the feed bar 46 are reciprocated endwise, that is to say, the looper shaft is shifted in one direction while the feed bar is shifted in the other and vice versa. 35 Since, as will be apparent from Fig. III, the looper shaft 30 and its appendages are so proportioned as to have a total weight equal substantially to that of the feed bar 46 and its appendages, the endwise movements of one will be balanced by the contrariwise endwise movements of the other. Moreover, since the retractive swing of the loopers 35 must of necessity take place concurrently with the rising movement of the feed dog 56 and vice versa, a balanced action is 40 also had between the oscillations of the looper shaft 30 and of the pivoted guideway 57 in which the feed bar 46 is effectively held and controlled against lateral flexure and vibration in its endwise movements. It accordingly follows that our improved looping and feeding mechanism is smooth and noiseless in its action and therefore favors 45 running of the sewing machine at high speeds. In order to adapt the machine for operation upon different kinds of material, the movements of the loopers 35 and the feed dog 56 may be increased or decreased simply by shifting the studs 41 and 64 of the links 37 and 61 respectively along the slotted extremities of the double arm rocker 42, 50 said studs being accessible for this purpose upon removal of the screw plugs shown at 73 and 74 in Figs. I and X from access openings in one side of the work arm 3.

Attention is also directed to the fact that the 55 component parts of the mechanism are of simple design and therefore easy to manufacture and assemble at low cost.

Having thus described our invention, we claim:

1. Looping and feeding mechanism for chain 70 stitch sewing machines comprising a looper shaft, a parallel feed bar, a double arm rocker medially fulcrumed to oscillate about a transverse axis intermediate the shaft and the bar, said rocker having slots longitudinally of its opposite ex- 75

tremities, a link pivoted at one end to the shaft and carrying a stud at its other end adjustable along the slot of one of the extremities of the rocker, another link similarly connecting the feed bar with the other extremity of the rocker, and means for actuating the rocker.

2. Looping and feeding mechanism for chain stitch sewing machines comprising a looper shaft, a parallel feed bar, a support wherein the bar is confined for axial reciprocation, said support being mounted on a transverse pivot, a double arm rocker medially fulcrumed on a transverse axis, a link connecting the shaft to one extremity of the rocker, another link connecting the feed bar to the other extremity of the rocker, and means for actuating the rocker and for oscillating the feed bar support on its pivot.

3. Looping and feeding mechanism for a chain stitch sewing machine having a horizontal rotary shaft at a level above a horizontal work supporting surface, said mechanism comprising a horizontal looper shaft, a parallel feed bar, a double arm rocker medially fulcrumed to oscillate about a transverse axis intermediate the looper shaft and the feed bar, means connecting the opposite extremities of the rocker respectively with the looper shaft and the feed bar, said looper shaft, feed bar, rocker and connecting means being all beneath the work supporting surface, and an actuating connection extending down from the rotary shaft aforesaid to the rocker.

4. Looping and feeding mechanism for a chain stitch sewing machine having a horizontal rotary shaft at a level above a horizontal work supporting surface, said mechanism comprising a horizontal looper shaft, a horizontal feed bar overlying the looper shaft and carrying a feed dog, a vertically-arranged double arm rocker medially fulcrumed to oscillate about a transverse axis intermediate the looper shaft and the feed bar, means whereby the pendant and upwardly extending extremities of the rocker are respectively coupled to the looper shaft and the feed bar, said looper shaft, feed bar, rocker and connecting means being all below the work supporting surface, and an actuating connection extending down from the rotary shaft to the rocker.

5. Looping and feeding mechanism for a chain stitch sewing machine having a horizontal rotary shaft at a level above a horizontal work supporting surface, said mechanism comprising a horizontal looper shaft, a horizontal feed bar overlying the looper shaft and carrying a feed dog, a vertically-arranged double arm rocker medially fulcrumed to oscillate about a transverse axis intermediate the looper shaft and the feed bar, means whereby the pendant and upwardly extending extremities of the rocker are respectively coupled to the looper shaft and the feed bar, said looper shaft, feed bar, rocker and connecting means being all below the work supporting surface, and a link extending down from an actuator crank on the rotary shaft aforesaid to the rocker.

6. Looping and feeding mechanism for a chain stitch sewing machine having a horizontal work supporting surface and a horizontal rotary shaft at a higher level, said mechanism comprising a horizontal looper shaft supported with capacity for endwise reciprocation and oscillation, a horizontal feed bar, a support pivoted on a transverse axis and guiding the feed bar for endwise movement, a double arm rocker medially fulcrumed

to oscillate about a transverse axis intermediate the looper shaft and the feed bar, means whereby the opposite extremities of the rocker are respectively connected to the looper shaft and the feed bar, said looper shaft, bar, rocker, pivoted support and connecting means being all below the work supporting surface, and separate connections extending down from the rotary shaft to oscillate the looper shaft, to actuate the rocker, and to oscillate the pivoted support for the feed bar.

7. Looping and feeding mechanism for a chain stitch sewing machine having a horizontal work supporting surface and a horizontal rotary shaft at a higher level, said mechanism comprising a horizontal looper shaft supported with capacity for endwise reciprocation and oscillation, a horizontal feed bar, a support pivoted on a transverse axis and guiding the feed bar for endwise movement, a double arm rocker medially fulcrumed to oscillate about a transverse axis intermediate the looper shaft and the feed bar, means whereby the opposite extremities of the rocker are respectively connected to the looper shaft and the feed bar, said looper shaft, bar, rocker, pivoted support and connecting means being all below the work supporting surface, and links extending down from actuating cranks on the rotary shaft and connected respectively to a crank arm on the looper shaft, to the rocker, and to the pivoted support for the feed bar.

8. The combination with looper and feeding mechanism for chain stitch sewing machines comprising an oscillating and endwise reciprocating looper shaft, a rocking and endwise reciprocating feed bar carrying a feed dog at one end thereof, and means for inducing simultaneous endwise movements of said looper shaft and feed bar in opposite directions; of a movable supporting guide in which the bar is guided in its endwise reciprocation, and a fixed guide which engages the feed bar beyond the movable guide and prevents said bar from rotating about its own axis.

9. The combination with looper and feeding mechanism for chain stitch sewing machines comprising an oscillating and endwise reciprocating looper shaft, a rocking and endwise reciprocating feed bar with a feed dog at one end thereof, and means for inducing simultaneous endwise movements of said looper shaft and feed bar; of a movable supporting guide in which the feed bar is guided in its endwise reciprocation, and a fixed guide which engages the feed bar adjacent the feed dog, and prevents said bar from rotating about its own axis.

10. The combination with looper and feeding mechanism for a chain stitch sewing machine comprising an oscillating and endwise reciprocating looper shaft, a rocking and endwise reciprocating feed bar and means for inducing simultaneous endwise movements of said looper shaft and feed bar in opposite directions, of a movable guide in which the feed bar is guided in its endwise reciprocation, and a fixed guide which engages the feed bar beyond the movable guide and prevents said bar from rotating about its own axis, said shaft with its appendages and said bar with its appendages being so proportioned and arranged as to substantially balance each other in their movements.

CLARENCE C. SMITH.
GEORGE SAUER.
